UNITED STATES PATENT OFFICE.

EVERT HOLLOWELL, OF KANSAS CITY, KANSAS.

HOSPITAL-BED.

1,266,268.

Specification of Letters Patent.

Patented May 14, 1918.

Application filed November 20, 1915. Serial No. 62,617.

To all whom it may concern:

Be it known that I, EVERETT HOLLOWELL, a citizen of the United States, residing at Kansas City, in the county of Wyandotte 5 and State of Kansas, have invented certain new and useful Improvements in Hospital-Beds, of which the following is a full, clear, and exact description, such as will enable others skilled in the art to which it appertains to make and use the same.

The present invention relates to bed stands for hospitals and seeks to provide a simple and effective form of bed stand, with a tilting and rotatable receiving table.

The tilting of the springs of bed stands is not new, but by providing safety stops to prevent accident from extreme angles of the receiving table, and combining means of rotating with the tilting, the result is a general utility hospital bed stand and operating table.

The present invention seeks to provide an improved bed stand with a rotatable and longitudinally tilting receiving table, the receiving surface of which is preferably formed of ordinary bed springs.

A further object of the invention is to so construct the receiving table that it will stand rigidly transversely of the bed stand 30 side rails so that patients may be placed thereon and removed therefrom without lifting them over the foot piece, and so that the receiving table may be used as an operating table.

A still further object of the invention is to provide safety stops so that the receiving table cannot be tilted beyond an angle that will safely allow the patient to remain thereon.

With these and other objects in view the invention consists in the shapes, improved features of construction, combinations and arrangements of parts hereinafter set forth, illustrated in the accompanying drawings 45 and more particularly pointed out in the appended claims.

In the drawings:

Figure 1 is a view in side elevation of the improved bed stand.

Fig. 2 is a view in side elevation of the improved bed stand illustrating the tilting of the receiving table of the improved bed stand.

Fig. 3 is a view in end elevation of the improved bed stand.

Fig. 4 is a view in side elevation of the bed stand with the receiving table in a rigid transverse position.

Fig. 5 is a plan view of the bed stand.

Fig. 6 is an enlarged fragmentary view. 60

Fig. 7 is an enlarged fragmentary sectional view taken on line *a*—*a* of Fig. 5.

Fig. 8 is an enlarged fragmentary sectional view taken on line *b*—*b* of Fig. 5.

The head piece 1, foot piece 2 and side 65 rails 3, are of common and well known construction, the side rails as shown being separable from the head and foot pieces in the usual manner, it being obvious that the side rails may be rigidly connected to the head 70 and foot piece if desired.

The supporting bar 4 spans the rails 3 transversely near the center of the length of the rails and is bolted thereto by the bolts 7, the rest bar 6 being loosely pivoted to the 75 supporting bar by the center bolt 5, the latter being provided with the spring 8, and nut 9 to resiliently hold the parts 4 and 6 more firmly in horizontal position, and the washer 10 being placed between the bars to 80 form a center bearing so that the rest bar may be more easily rotated over the supporting bar.

To the rest bar 6 are secured the side frames 11, the lower side 12 of the frames 85 being preferably straight and one parallel with the other for the central portion of their length equal to the distance transversely across the side rails 3, and the lower side 12 of the frames being of the same 90 height and even with the upper side 13 of the side rails, so that when the frames are thrown to transverse position as shown in Fig. 4 they will rest rigidly on the side rails.

To the ends 14 of the frames 11 is secured 95 the cross member 15, while to the ends 16 is secured the cross member 17, the cross members being secured to and supporting the receiving table 18, the latter being preferably of ordinary bed spring construction. 100

To the cross member 17 is pivoted at 19 the adjusting bars 20, which are provided with the holes 21 to engage the pins 22 for the purpose of holding the receiving table 18 level as shown in Fig. 1 and in the tilted 105 positions shown in full lines and in dotted lines of Fig. 2, also in any intermediate tilted position corresponding to the position of the holes.

The bars 20 are held in position on the 110

pins 22 by the keeper pins 23, which are attached to the members 24 by the chains 25 to prevent displacement and loss of the pins 23.

The rectangular strip of metal 26 is secured to the cross member 17 and forms sockets 27 in which may be inserted the foot rests 28, for the purpose of securing a patient's feet in certain positions.

The hole 29 is provided for the insertion 10 of the pins 30 for the purpose of holding the receiving table 18 in longitudinal position on the rails 3.

It will be noticed that the cross members 15 and 17 are longer than the width over the frames 11 and project beyond the frames to engage the side rails 3 when the receiving table is tilted to the extreme position in either direction, this feature serving as a safety device to prevent the tilting of the 20 table to a position that would prevent the patient from remaining thereon.

The receiving table 18 is turned transversely as shown in Fig. 4 and in dotted lines of Fig. 5 so that attendants carrying patients on stretchers may step over the rails and place the patient on the table without having to lift them over the foot piece 2 as is usually the case. A further advantage 25 of turning the receiving table transversely 30 and allowing it to rest firmly by contact of the frames 11 on the rails 3, lies in the fact that in this position the table may be employed as an operating table and dispense with much of the moving of patients from 35 the bed to the operating room and return.

What I claim, is:—

1. In a hospital bed the combination of a bedding receiving frame, a bar secured to the sides of said bedding receiving frame, a 40 bar secured to the side rails of a bed, said first mentioned bar supported by said last mentioned bar, means to normally hold said bedding receiving frame in horizontal position, means whereby said bedding receiving frame can be tilted on said last mentioned bar and turned in a horizontal direction, and means to prevent said bedding receiving frame from tilting when turned out of 45 alinement with the side rails of the bed.

Copies of this patent may be obtained for five cents each, by addressing the "Commissioner of Patents, Washington, D. C."

2. In a hospital bed the combination of 50 a bedding receiving frame, a bar secured to the side rails of a bed, a bar secured to the sides of the bedding receiving frame of said bed, means pivotally connecting said bars whereby said frame may be revolved in a 55 horizontal position, said means adapted to allow said frame to be tilted between said rails and means to prevent said frame from being tilted when revolved out of alinement with said side rails.

3. In a hospital bed the combination of a bedding receiving frame, a bar secured to the side rails of a bed, a bar secured to the sides of the bedding receiving frame of said bed, means arranged on said bars whereby 65 said frame may be revolved in a horizontal position, said means adapted to allow said frame to be tilted between said rails, means to prevent said frame from being tilted below the rails of said bed, and means to prevent 70 said frame from being tilted when revolved out of alinement with said side rails.

4. In a bed, the combination of a transverse bar connecting and secured to the side rails of a bed, a transverse bar secured to 75 and spread across the bedding receiving frame of the bed, said last mentioned bar resting upon a washer on said first mentioned bar, and said bars pivotally connected by a bolt therethrough whereby said bedding receiving frame can be thrown out of 80 horizontal alinement with the side rails and revolved horizontally.

5. In a hospital bed the combination of a bedding receiving frame, a rest bar secured 85 to the sides of said bedding receiving frame, a supporting bar secured to the side rails of a bed, said rest bar supported by said supporting bar, and said rest bar and said supporting bar connected by a loosely fitting 90 bolt whereby said bedding receiving frame is adapted to tilt and to revolve.

In testimony whereof I affix my signature in the presence of two witnesses.

EVERT HOLLOWELL.
